DESIGN FOR A HANGER FOR UMBRELLAS, PURSES, OR THE LIKE

Clara Virginia Eshbach, York, Pa.

Application June 1, 1939, Serial No. 85,283

Term of patent 14 years

To all whom it may concern:

Be it known that I, Clara Virginia Eshbach, a citizen of the United States of America, residing at York, in the county of York and State of Pennsylvania, have invented a new, original, and ornamental Design for a Hanger, for Umbrellas, Purses, or the like, of which the following is a specification, reference being had to the accompanying drawing, forming part thereof, wherein:

Fig. 1 is a perspective view of a hanger, for umbrellas, purses, or the like, showing my new design;

Fig. 2 is a side view thereof;
Fig. 3 is a front view thereof; and
Fig. 4 is a top plan view.

I claim:

The ornamental design for a hanger, for umbrellas, purses, or the like, as shown.

CLARA VIRGINIA ESHBACH.
